UNITED STATES PATENT OFFICE.

SCOTT E. ALLEN, OF LOS ANGELES, CALIFORNIA, ASSIGNOR TO SWINGSPOUT MEASURE CO., A CORPORATION OF CALIFORNIA.

SPRING VALVE FOR SWINGSPOUT MEASURES.

Application filed August 13, 1923. Serial No. 657,027.

To all whom it may concern:

Be it known that I, SCOTT E. ALLEN, a citizen of the United States, residing at Los Angeles, in the county of Los Angeles, State 5 of California, have invented a new and useful Spring Valve for Swingspout Measures, of which the following is a specification.

My invention relates to spring valves for swingspout measures such as are used at oil 10 service stations for measuring lubricating oil and pouring the same into automobile crank case reservoirs.

The general object of my invention is to provide a measure of the character above 15 stated including adjustable means for maintaining the measure valve fluid-tight under varying conditions.

A more particular object is to provide resilient means bearing against the small end 20 of one of the frusto conical valve members of a frusto conical valve to hold said member seated on the other valve member in fluid-tight relationship therewith, and means for adjusting the pressure of said resilient 25 means on said valve member as required to maintain such fluid-tight relationship.

Further objects and advantages will be made evident hereinafter.

Referring to the drawing which is for 30 illustrative purposes only:

Fig. 1 is a side elevation partly broken away and shown in section of a swingspout embodying my invention.

Fig. 2 is a bottom plan view of said swing- 35 spout shown in Fig. 1.

Fig. 3 is a fragmentary vertical longitudinal section of said swingspout taken on line 3—3 of Fig. 2.

Fig. 4 is a perspective view of the re- 40 silient valve engaging element.

In the drawing, 1 indicates a casing; 2 a bottom; 3 a measuring receptacle formed by said casing and said bottom; 4 a rim extending below said bottom; 5 an outlet conduit 45 leading from the bottom of said measuring receptacle; 6 a conical controlling valve into which said conduit leads; 7 a spout connected to said valve; 8 a measuring edge of the non-spill top of the receptacle 3; and 9 a 50 handle secured to the rear of said casing; all of these parts being of standard construction. The rim 4 is bent inwardly from the front thereof in U-shaped formation as indicated at 10, forming the walls of a pocket 55 11 extending inwardly from the front of the

rim below the bottom 2, in which pocket is located the valve 6. As shown, the valve 6 comprises an inner and fixed frusto conical shell 12 and an outer frusto conical shell 13 seated and movable on said inner shell as 60 a bearing. The inner shell 12 extends longitudinally between the side walls of the pocket 11 and is jointed at its ends to said side walls, one of said side walls being provided with a valve inlet opening 14, through 65 which the conduit 5 communicates with the inner valve shell 12. The inner valve shell 12 has an outlet port 15 and the outer valve shell 13 has an outlet port 16 in communication with the valve end of the spout 7, to 70 which shell said spout is connected, the port 16 being closed by the wall of the inner valve shell 12 when the spout is turned into its upwardly extended position, (in which position the spout extends forwardly through 75 the open front of the pocket 11 and upwardly in front of the measure, as shown in full lines in Fig. 1) and said port 16 being adapted to coincide with the port 15 when the spout 7 is turned downwardly as indicated in dotted lines in Fig. 1, in which latter position the valve is opened and the contents of the receptacle 3 allowed to pass out of said receptacle through the conduit 5, the valve shell 12, the ports 15 and 16, and the 80 spout 7.

A flat spring 20 is formed with a tongue 21 at one end and a fork 22 at its other end, said fork comprising a pair of arms 23, the crotch 24 of said fork between said arms being arcuate. The tongue 21 extends through a vertical slot 25 in the rear wall of the pocket 11 so that the fork 22 straddles the valve shell 12 near its small end with its arms 23, engaging the small end of the 90 outer valve shell 13, the arcuate crotch 24 of said fork accommodating said shell 12. A set screw 26 is seated in one of the side walls of the pocket 11 in position to engage the spring 20 for adjusting the pressure of said spring against said small end of said outer valve shell 13, to hold said outer shell firmly seated on the inner valve shell 12, whereby the shells 12 and 13 are 95 maintained in fluid-tight relationship under 100 varying conditions.

I claim as my invention:

1. In a spring valve swingspout measure, a swingspout outlet valve comprising: an inner fixed member; an outer movable mem- 110

ber disposed on said inner member, the ends of said inner member extending beyond the ends of said outer member; engagement means extending around said inner member and engaging an end of said outer member; and means for regulating the pressure of engagement of said engaging means with an end of said outer member.

5 2. In a spring valve swingspout measure, 10 the combination of a frusto-conical swingspout outlet valve comprising an inner member and an outer member; a flat spring engaging the small end of the outer frusto-conical member of said valve for maintaining 15 said member firmly seated on the inner frusto-conical member of said valve; and a set screw engaging said flat spring for varying 20 the pressure of said spring against said frusto-conical valve member, as conditions require, to hold said outer conical valve member firmly seated on said inner conical valve member, said outer valve member being movable upon said inner member as 25 a bearing.

25 3. In a spring valve swingspout measure, 30 the combination of a frusto-conical swingspout outlet valve comprising an inner member and an outer member; a flat spring formed with a tongue on one end for engaging 35 a slot in a wall of the measure for holding the other end of said spring in engagement with the small end of the outer frusto-conical member of said valve for holding 40 said outer member firmly seated upon said inner valve member.

4. In a spring valve swingspout measure, 45 the combination of a frusto-conical swingspout outlet valve comprising an inner member and an outer member; a flat spring formed with a tongue on one end for engaging 50 a slot in a wall of the measure for holding the other end of said spring in engage-

ment with the small end of the outer frusto-conical member of said valve for holding 45 said outer frusto-conical member firmly seated upon said inner frusto-conical valve member; and means for engaging said flat springs for adjusting the pressure thereof against said small end of said outer valve member as conditions require.

5. In a spring valve swingspout measure, 55 the combination of a swingspout outlet valve comprising a fixed inner member and a movable outer member; a flat spring formed with a tongue on one end for engaging 60 a slot in a wall of the measure for holding the other end of said spring in engagement with the small end of the outer member of said valve for holding said outer member firmly seated upon said inner conical valve member; and a set screw for engaging 65 said flat spring for adjusting the pressure thereof against said small end of said outer valve member as conditions require.

6. In a spring valve swingspout measure, 70 a swingspout outlet valve comprising: an inner fixed frusto-conical member; an outer movable frusto-conical member disposed on 75 said inner frusto-conical member, the ends of said inner frusto-conical member extending beyond the ends of said outer frusto-conical member; engaging means extending around said inner frusto-conical member and engaging the small end of said outer frusto-conical member; and means for regulating 80 the pressure of engagement of said engaging means with the small end of said outer frusto-conical member.

In testimony whereof, I have hereunto set 80 my hand at Los Angeles, California, this 6th day of August, 1923.

SCOTT E. ALLEN.
